SEPARATOR

Gordon E. Randall, Schenectady, N. Y., assignor
to General Electric Company, a corporation of
New York

Application February 25, 1938, Serial No. 192,657

5 Claims. (Cl. 183—110)

The present invention relates to liquid vapor separating arrangements for separating liquid particles contained in vapor such as are used, for instance, in connection with steam turbine arrangements to dry or to remove condensate from the steam after it has passed through several high pressure stages.

The object of my invention is to provide an improved construction of liquid vapor separating arrangements whereby liquid particles contained in vapor may be effectively separated therefrom.

For a consideration of what I believe to be novel and my invention, attention is directed to 15 the following description and the claims appended thereto in connection with the accompanying drawing.

In the drawing, Fig. 1 illustrates an elastic fluid turbine arrangement embodying my invention; Fig. 2 is an enlarged sectional view of a 20 part of Fig. 1; and Fig. 3 shows a modification of my invention.

The arrangement of Fig. 1 comprises a high pressure turbine 10 with an inlet conduit 11 and 25 an exhaust end 12, which latter is connected by a cross-over conduit 13 to a low pressure turbine 14 with an exhaust end 15. During operation, elastic fluid while flowing through the high pressure turbine 10 and giving up some of its available energy becomes moist. Liquid particles, 30 such as water, contained in the steam are destructive when admitted to the low pressure turbine. Due to the high inertia of these particles they cause considerable wear of the bucket wheel 35 and diaphragm blades and in addition effect corrosion and erosion of the steel from which these blades are made. The liquid particles therefore 35 are separated from the elastic fluid on its flow through the cross-over conduit 13 by means of a liquid vapor separating device 16. This device, 40 as shown in Fig. 2, comprises a body 17 which constitutes in substance a conduit with flanged openings 18 and 19 for connection to the exhaust end 12 of the high pressure turbine and the inlet of the low pressure turbine respectively. The lower portion of the body 17 has another flanged opening 20 which is connected to a vessel 21 from 45 which liquid may be drained through a drain conduit 22 including a valve 23. The direction of flow of elastic fluid through the body 17 is from the left to the right, as indicated by arrows. The separation of liquid from vapor is effected by means including a deflecting wall 24 which in the present instance is in the form of a 50 substantially conical element having a point 25

directed towards the direction of flow of fluid. This cone, as shown in the drawing, is formed by a curved line revolving about an axis to form a concave deflecting surface 26. The outer edge of the cone or deflecting element 20 is connected to 5 an annular channel 27 which is of substantially toroidal shape forming an annular opening 28. An edge 29 of the channel member is secured or sealed to the rear surface of the cone and the lower portion of the channel member is connected to a discharge conduit 30 projecting into the vessel 21. The channel 27 and the cone 26 are supported by means of brackets 31 on the body 17.

During operation, liquid particles contained in 15 the elastic fluid impinge on the deflecting surface 26 of the cone 24 and flowing along this surface these particles are conducted into the channel 27, whence they are discharged through the conduit 30 into the vessel 21. Liquid thus 20 accumulating in the lower portion of the vessel 21 may be drained therefrom by opening the valve 23. The opening of the valve 23 may be effected manually or, as shown in the present instance, 25 automatically by means including a suitable mechanism 32 for opening the valve 23 as soon as the liquid in the vessel 21 reaches a predetermined level.

While the arrangement of Figs. 1 and 2 shows 30 a liquid vapor separating device with a single deflecting surface, the arrangement of Fig. 3 shows a device with several such deflecting surfaces. These surfaces may be arranged in parallel or in series with regard to the flow of elastic fluid. In the present instance the arrangement of Fig. 35 3 comprises a high pressure turbine 35 which has a last bucket wheel 36 disposed within a fabricated cross-over conduit 37 for conducting elastic fluid discharged from the high pressure turbine to a double-flow low pressure turbine (not shown). An arrangement of this kind is more 40 fully disclosed in the Patent No. 2,102,416 issued December 14, 1937 to the administrator of O. Junggren and assigned to the same assignee as the present application. The separation of liquid 45 from the vapor or elastic fluid is effected in the cross-over conduit 37 by means of two frusto-conical deflecting members 38 and 39 with concave deflecting surfaces corresponding to the surface 26 in Fig. 2. The outer edges or rims of these members project into and are secured to channel members 40 and 41 respectively. The latter are supported by brackets 42 and 43 respectively on the wall of the cross-over channel 50 37. The lower portions of the channel mem- 55

bers 40, 41 are connected by drain conduits 44 and 45 respectively to a chamber 46 from which liquid may be drained.

During operation liquid particles contained in 5 the elastic fluid discharged from the bucket wheel 36 impinge on the deflecting surfaces of the members 38 and 39, whence the liquid is forced by inertia into the channel members 40 and 41 to be drained therefrom through the conduits 40, 45 into the chamber 46. The inner edge of the deflecting member 39 in the present instance engages the outer wall of a bearing 47 for supporting the shaft or shafts of the high pressure and low pressure turbines.

15 With my invention I have provided an improved construction and arrangement for liquid vapor separating devices. Such devices broadly include a member having a deflecting surface inclined towards the direction of flow of fluid and 20 an outer edge or rim projecting into a channel, which latter has an edge secured to the rear side of the deflecting member.

Having described the method of operation of 25 my invention, together with the apparatus which I now consider to represent the best embodiment thereof, I desire to have it understood that the apparatus shown is only illustrative and that the invention may be carried out by other means.

What I claim as new and desire to secure by 30 Letters Patent of the United States is:

1. Liquid vapor separating device comprising a conduit, a deflecting member having an outer edge and a surface inclined towards the direction of elastic fluid, and a channel member into 35 which the outer edge of the deflecting member projects, said channel member being sealed to the rear surface of the deflecting member.

2. Liquid vapor separating device comprising a conduit for conducting elastic fluid, a conical

deflecting member pointing in a direction opposite to that of the flow of fluid through the conduit, an annular channel member into which the outer edge of the deflecting member projects, said channel member having an edge secured to 5 the rear surface of the conical deflecting member, and means for draining liquid from the annular channel member.

3. Liquid vapor separating device comprising a body having flanged inlet and outlet openings, 10 a conical deflecting member with its axis horizontally disposed within the body and pointing in a direction opposite to that of the flow of fluid therethrough, an annular channel into which the outer edge of the deflecting member 15 projects, said channel being sealed to the rear of the deflecting member, and means for draining liquid from the channel.

4. Liquid vapor separating device comprising a body having flanged inlet and outlet openings, 20 a frusto-conical deflecting member with its axis horizontally disposed within the body and pointing in a direction opposite to that of the flow of fluid therethrough, an annular channel into 25 which the outer edge of the deflecting member freely projects to define with the channel an annular groove in the rear of the deflecting member, said channel being secured to the rear of the deflecting member, and means for draining liquid from the channel.

5. Liquid vapor separating device comprising a conduit, a plurality of frusto-conical deflecting members having surfaces disposed in the conduit and pointing towards the direction of flow of fluid therethrough, separate annular channel 35 members substantially surrounding the outer edges of the deflecting members, and a drain conduit for each channel member.

GORDON E. RANDALL.
